UNITED STATES PATENT OFFICE.

ERNST KARL ALEXANDER BAUMANN, OF STUTTGART, GERMANY.

AEROPLANE.

Application filed November 26, 1923. Serial No. 677,086.

To all whom it may concern:

Be it known that I, ERNST KARL ALEXANDER BAUMANN, a citizen of Germany, residing at Stuttgart, in the State of Wurtemberg, Germany, have invented certain new and useful Improvements in Aeroplanes; and I do hereby declare the following to be a full, clear, and exact description of the invention, such as will enable others skilled in the art to which it appertains to make and use the same.

My invention relates to improvements in aeroplanes, and more particularly in the construction of the supporting planes, and the object of the improvements is to provide an aeroplane in which the sustaining power may be regulated so as to attain a maximum. With this object in view my invention consists in providing the top wall of the plane or planes with a slot or slots disposed longitudinally of the plane and forcing currents of air through the slots for sweeping away the dead air or whirls produced on the top face of the plane and reducing the sustaining power. By thus constructing the slots the strength of the plane is not interfered with, the plane comprising a rigid frame work or structure adapted to take up the strains exerted thereon in the flight. Another object of the improvements is to provide a sustaining plane which is provided transversely of the plane and on the top or bottom face thereof with slots which are likewise provided with means for blowing currents of air therethrough for sweeping away the whirls produced at the outer sides of the planes and thus reducing the resistance of the plane passing through the air.

For the purpose of explaining the invention several examples embodying the same have been shown in the accompanying drawing in which the same reference characters have been used in all the views to indicate corresponding parts. In said drawing,

Fig. 1 is a cross-section of the plane taken longitudinally of the aeroplane,

Fig. 2 is a similar cross-section showing a modification,

Fig. 3 is a plan view of Fig. 2 on a reduced scale,

Fig. 4 is a diagrammatical plan view showing a modification in which the plane is provided at its sides with slots disposed symmetrically relatively to the longitudinal axis of the aeroplane and longitudinally thereof,

Fig. 5 is a cross-section on an enlarged scale taken on the line 5—5 of Fig. 4,

Figs. 6 to 8 are similar sectional elevations showing modifications of the arrangement of the longitudinal slots,

Fig. 9 is a plan view showing a modification in which the plane is provided both with longitudinal and transverse slots, and

Fig. 10 is a cross-section on an enlarged scale taken on the line 10—10 of Fig. 9.

In the construction shown in Fig. 1 the top wall 1 of the plane is provided with a slot 2 disposed longitudinally of the plane and opening rearwardly in the direction 70 of the flight. The bottom wall 1' of the plane is provided with holes 3 adapted to be throttled more or less by means of gates 5 operated by ropes 4. In a modification I provide the throttling members in position 75 for throttling the slots 2. In the flight of the aeroplane the air rushes through the holes 3 so as to produce a certain pressure within the plane, and it is discharged through the slots 2 in a direction for sweeping the top face of the plane, as is indicated by the arrow α . Thereby the dead air is swept away from the plane.

In the modification shown in Figs. 2 and 3 a plurality of slots 21 are provided one behind the other in the top wall 11 and the slots communicate with tubes or pipes 6 connected with a supply or independent supplies of compressed air such as a fan or compressor 7. The tubes or pipes 6 are made from 80 thin material such as thin fabric, or sheet metal. For regulating the supply of compressed air to the slots 21 valves 8 are provided between the pipes 6 and the compressor 7.

In Figs. 4 and 5 I have shown the arrangement of lateral slots 9 disposed in the top wall 12 and symmetrically of and substantially parallel to the longitudinal axis of the aeroplane, and means are provided for blowing currents of air through said slots outwardly and in a direction opposite to the movement of the whirls produced at the margins of the plane, as is indicated by arrows 10. It will be understood that ordinarily lateral slots 9 are provided together with the longitudinal slots 2 or 21 shown in Figs. 1 to 3, and that when provided in the construction shown in Fig. 1 the compressed air is supplied from the hollow of the plane. In the modification shown in Fig. 6 slots 91 are provided at the bottom face of the plane.

Arrows 101 indicate the direction of the discharge of the air. In Fig. 7, I have shown a modification in which lateral slots 92 and 93 are provided both in the top and bottom walls of the plane, the direction of the flow being indicated by arrows 91 and 93. A similar arrangement of slots 94 and 95 is shown in Fig. 8, the direction of the flow being indicated by arrows 14 and 15. The arrangement of the slots 94 and 95 shown in Fig. 8 is more simple in construction as compared to the example shown in Fig. 7.

Figs. 9 and 10 show a construction in which lateral and longitudinal slots 96, 97 are combined in a single aeroplane, the bottom wall showing also an additional opening 98 similar to that which is shown in Figures 6 and 8. By the said slots the production of whirls is avoided.

While in describing the invention reference has been made to particular examples embodying the same, I wish it to be understood that my invention is not limited to the construction shown in the drawing and that various changes may be made in the arrangement and the form of the slots without departing from the invention.

I claim:

1. In an aeroplane, a carrying wing having a lower surface provided near the lateral edges with slots symmetrical to the central portion of the carrying wing for the purpose of forcing compressed air therethrough to reduce eddy currents. 30

2. In an aeroplane, a carrying wing having an upper surface and a lower surface provided with slots symmetrical to the central portion of the carrying wing and approximately parallel to the lateral edges for the purpose of passing compressed air therethrough to suppress marginal eddy currents. 35

3. In an aeroplane, a carrying wing which is provided with slots parallel to the front edge thereof and extending over the entire length of the wing and with slots at the ends 45 of said first named slots, contiguous thereto, extending approximately parallel to the lateral edges of the wing and parallel to each other to cause compressed air to be forced without interruption through said slots in a stream or ribbon shape over the upper surface of the carrying wing to blow away dead air and to suppress marginal eddy currents. 50

In testimony whereof I hereunto affix my signature.

ERNST KARL ALEXANDER BAUMANN.
